PLASTIC COATED FABRIC OR SIMILAR ARTICLE

John C. Siegmann, Toledo, Ohio, assignor to Interchemical Corporation, New York, N.Y., a corporation of Ohio

Filed Mar. 10, 1961, Ser. No. 64,223

Term of patent 14 years

(Cl. D87—3)

FIG. 2.

FIGURE 1 is a top plan view of a plastic coated fabric or similar article, showing my new design, the repeat unit of which is substantially contained between the two horizontal dot and dash lines and the two vertical dot and dash lines.

I claim:

The ornamental design for plastic coated fabric or similar article, as shown and described.
